UNITED STATES PATENT OFFICE.

EMIL H. GOETZE, OF WALLINGFORD, CONNECTICUT, ASSIGNOR TO INTERNATIONAL SILVER COMPANY, OF JERSEY CITY, NEW JERSEY, AND MERIDEN, CONNECTICUT, A CORPORATION OF NEW JERSEY.

● DESIGN FOR A HANDLE FOR VESSELS OR SIMILAR ARTICLES.

SPECIFICATION forming part of Design No. 36,426, dated July 14, 1903.

Application filed June 15, 1903. Serial No. 161,633. Term of patent 3½ years.

To all whom it may concern:

Be it known that I, EMIL H. GOETZE, a citizen of the United States, residing at Wallingford, in the county of New Haven and State of Connecticut, have invented a new, original, and ornamental Design for Handles for Vessels or Similar Articles, of which the following is a brief specification, reference being had to the accompanying drawings, forming part thereof, for the special and distinguishing features of the design, and in which—
Figure 1 is a view in side elevation of the

handle, showing my new design. Fig. 2 is a view in elevation in a plane at right angles to the plane of view of Fig. 1.

What I claim as new, and desire to secure by Letters Patent, is—

The ornamental design for handles for vessels or similar articles, as shown.

EMIL H. GOETZE.
